UNITED STATES PATENT OFFICE.

HENRY PETERS, OF BROOKLYN, NEW YORK, ASSIGNOR OF ONE-HALF TO LANCELOT
BRISBAIN BEATH, OF TORONTO, CANADA.

EXPANDED-METAL LATHING.

No. 902,602.

specification of Letters Patent.

Patented Nov. 3, 1908.

Application filed December 16, 1907. Serial No. 406,669.

To all whom it may concern:

Be it known that I, HENRY PETERS, of the city of Brooklyn, in the county of Kings, in the State of New York, one of the United States of America, have invented certain new and useful Improvements in Expanded-Metal Lathing, of which the following is the specification.

My invention relates to improvements in expanded metal lathing, and the object of the invention is to devise a form of metal lathing of this class particularly adaptable to ceilings, which will insure of the plaster while setting remaining in position, and thereby obviate the cracking or falling of plaster, which is so commonly incident to plaster when applied to the expanded metal lathing now commonly in use.

A further object is to add strength to the lathing and make it capable of resisting the pressure of the trowel in that it will not recede while the plastering is being done, and thus insure a flat, plane surface of the plaster after the first coat has been applied, in short make an expanded metal lathing not flexible as the ordinary lathing now in use, but rigid, strong and durable.

A still further object is to prevent any liability of the action of rust on the fin-like bridging from severing such bridging and thus allow the plaster to crack or fall, and at the same time so key and support the plastering in position as to obviate any liability, if the fin-like bridging should be broken, of such plaster falling.

A yet further object is to make the lathing stiff enough, so that the necessity of providing an expensive superstructure for the lathing may be avoided.

To effect these objects I have constructed my improved expanded metal lathing of sheet metal preferably steel having longitudinal channel ribs with the channel uppermost, such ribs being connected by fin-like bridging, each fin of which is at the central portion given a quarter turn and being preferably arranged in a depressed or arch-like form as hereinafter explained.

Figure 1, is a perspective view of a very small portion of a ceiling showing the application of my invention. Fig. 2, is a section. Fig. 3, is a section of the lathing at right angles to that shown in Fig. 2. Fig. 4, is a sectional detail of the lathing showing a modification of the form shown in Fig. 2.

In the drawings like letters of reference indicate corresponding parts in each figure.

Heretofore in expanded metal lathing the key has been of such a nature that the mesh being formed of inclined surfaces throughout forms a series of longitudinal fins and bridging fins connecting them practically on edge, and thus forming little if any support for the wet mortar or plaster. The result has been that in putting up the plaster it would not remain in position, but fall before it had time to set. It is with the object of avoiding this and other objections, and producing an expanded metal lathing capable of retaining the plaster while setting and at the same time producing an even surface that my invention is particularly designed.

A is a portion of expanded metal lathing, which is provided with the channel ribs A' of any suitable form of channel, the channel, of course, being uppermost. The portion A is made in much the same manner as other expanded metal lathing, that is to say as far as expanding the metal is concerned, the channel ribs A' being connected together by the fin-like bridges A², which extend in somewhat diagonal form between the channel ribs as indicated in Figs. 1 and 2. Each fin A² is given a twist or turn at about an angle of forty-five degrees from the horizontal as indicated in Fig. 3, the ends of each fin where it is connected to the channel being practically on the horizontal or flush with the general plane of the lathing. The fins are formed by slitting the metal obliquely with reference to the channels, then expanding and so giving the strips a quarter turn, and, at the same time, leaving openings between them as a result of the expansion.

B is the plaster, which is forced up by the trowel through the fin-like bridges when in the wet state passing into the channel-like ribs A' and being keyed or retained and supported in position by such channel ribs from rib to rib. The bridging fins between are for the most part at an angle of forty-five degrees to the general construction of the lathing to form also a support for the plaster when in its wet state. The channel ribs A', however, form the major means of retaining the plaster in position from rib to rib, although, of course, the fins A² being set as they are materially help in supporting the plaster.

When the plaster sets and dries the channel ribs A' form a very strong reinforcement for

2
the plaster and such channel ribs being secured in position by any suitable fastening means, strengthen the whole plastic structure. Even should the ends of the fins become rusted off still the plaster would not fall on account of keying or supporting the plaster from one rib to the other.

5 In Fig. 4, I show the fins A⁴ with a downward bulge or arch-like sweep, this form being an alternative form to that shown in Fig. 2, in which the fins A² extend practically straight across. The reverse arch form of fins A⁴ present an increased resistance to the trowel when the plaster is applied and generally strengthen the structure when the plaster is set and hardened. In addition to this, the amount of plaster required is materially reduced, as, of course, it necessarily will be thinner at the crown of the arch.

What I claim as my invention is:

20 A metal lathing comprising a web having a series of parallel channel ribs with all the channels uppermost and bars connecting the upper edges of the channel ribs and formed up, when the web is expanded and as a result 25 of the expansion, at an angle out of the general plane of the web so as to leave intervening spaces, and being bent from their ends towards the center so as to form a reverse archlike structure with the bottom substantially flush with the bottom of the channels and the top forming an open work channel between the channel ribs as specified.

30 HENRY PETERS.
